UNITED STATES PATENT OFFICE.

JAMES P. WALLACE, OF BURLINGTON, IOWA.

IMPROVEMENT IN PENS.

Specification forming part of Letters Patent No. **222,847**, dated December 23, 1879; application filed October 24, 1879.

To all whom it may concern:

Be it known that I, JAMES P. WALLACE, of Burlington, Des Moines county, Iowa, have invented a new and useful Improvement in the Manufacture of Gold Pens, of which the following is a specification.

Figure 1 of the drawings is a representation of my improvement on a plan view. Fig. 2 is one of the nibs of a pen with the improvement attached.

The nature of my improvement consists in the securing, by soldering or otherwise, upon the outside or inside of the nibs of a gold pen of two reciprocal cross tongues or ribs, preferably of gold.

A A represent the nibs of a gold pen, upon one of which the cross tongue or rib B' is secured so that its point may rest upon the other nib. Upon the other nib is secured the tongue or rib C, preferably similar to the rib B, so that its point may rest upon the opposite nib. This forms a secure fastening by

which the nibs are prevented from crossing each other, and are held firmly in their respective places, while the elasticity of the pen is preserved.

Of course the cross tongues or ribs B and C can be secured at any desired angle and at any distance from each other upon the nibs. The number of tongues need not be confined to two.

What I claim as new, and desire to secure by Letters Patent, is—

A gold pen provided with reciprocal cross tongues or ribs, substantially as shown and described, for the purpose named.

In testimony whereof I have hereunto subscribed my name in the presence of two witnesses.

JAMES P. WALLACE.
